CAPPING ARRANGEMENT FOR ELECTRONIC VALVES

Bernhard Erber, London, England

Application November 25, 1942, Serial No. 466,839
In Great Britain March 16, 1942

9 Claims. (Cl. 250—27.5)

This invention relates to electronic valves and it refers particularly to the mounting of the cap upon the bulb and the connection of the leading in wires to the pins or other contacts on the cap.

As hitherto constructed a cap is employed which is of such form that the copper or other leading in wires have to be passed through holes at the bottom of the cap and usually through the pins, which in this case are of tubular form the bodies of the pins being moulded into the Bakelite or other material of which the cap is formed, the outer ends of the wires being each secured to one end of the protruding part of a pin by soldering it to said pin. In such cases as those in which the pins are solid rods or split longitudinally, the wire is passed through a hole in the Bakelite cap and is soldered to the pins near the point at which the pins are moulded in the cap.

The number of pins may vary according to the valve and may be from 4 to 9 through each of which a wire has to be threaded.

This threading of the tubes with the wires requires considerable care, first in finding the right hole for a particular wire, and secondly in avoiding short circuits due to two wires being crossed, the operatives, usually girls, requiring considerable training before they obtain the necessary degree of skill to enable production to reach a satisfactory degree. The present invention has for its object certain improvements whereby the aforesaid objections may be overcome.

In accordance with the present invention, instead of forming holes in the cap for the passage of the wires the said cap is provided with longitudinal slots or grooves said slots or grooves extending from the outer periphery of the cap to the pins one slot or groove being provided for each pin and also the pins themselves may be provided with a longitudinal slot or opening. The term "incisions" as used in some of the appended claims is to be understood as to include the slots as well as the grooves just mentioned, regardless of any special method for forming such slots or grooves. The wires coming out of the valves are put into the slots or grooves as the case may be and the cap is fixed in the normal way and the wires soldered at the end of the slotted pin or at any other convenient point when the pin has no slot. The same arrangement can be used for caps with side contacts.

To preserve the strength of the cap a tube or ring may be pushed over the cap and this tube can be made from either Bakelite, metal or any other material so that the cap is no longer weak-

ened by the slots. This tube can be built also as a cap having a rim at the bottom or with a bottom with holes of any shape so that this cap can be pushed over the slotted cap. The length of this second cap need not necessarily be that of the slotted cap. This cap or ring may only be necessary when applying the cap to the bulb and may be later removed should it be found that the cap is sufficiently strong without it.

In order that the invention may be the better understood, reference is made to the accompanying drawings in which:

Fig. 1 is a view showing the general appearance of a valve embodying the present invention.

Fig. 2 is a plan as seen from the lower end of the valve.

Fig. 3 is a sectional view of the cap and a strengthening member taken upon line A—A Fig. 2, looking in the direction of the arrow X.

Fig. 4 is a plan with the strengthening cap removed.

Fig. 5 is a side view of the cap with the strengthening member omitted.

Fig. 6 is a plan of one form of strengthening member removed from the cap.

Fig. 7 is a plan of an alternative form of a strengthening cap, to wit, of the strengthening cap which is shown in section in Figure 3.

Fig. 8 is a plan showing an alternative form 30 of the invention in which grooves are provided for the leading in wires in place of slots.

Fig. 9 is a sectional view showing more clearly the arrangement of the leading in wire where grooves are used in place of slots.

Fig. 10 is an elevational view of a valve having side contacts.

Fig. 11 is a plan of the lower end of a valve having side contacts according to Fig. 10.

Fig. 12 is an elevational view showing a modified arrangement to that shown in Figs. 10 and 11 and

Fig. 13 is a plan.

Figure 14 is a perspective view of the sleeve cap.

Referring to the accompanying drawings in which 1 indicates the valve and 2 the cap, 3 indicates slots extending lengthwise of the cap and across the closed end of the cap to the pins 4 as clearly shown in Figs. 4 and 5 of the drawings.

In order to strengthen the cap a sleeve 6 may be provided adapted to fit tightly over the cap, its attachment thereto being further assisted by the use of a suitable cement or adhesive, or the attachment of the sleeve to the cap may be effected by means of a screw or bayonet joint connection.

Instead of employing a sleeve of the same length as the cap 2, rings may be provided which may be located at suitable points along the length of the cap to which they are secured by means of a suitable cement or adhesive should it be desired to retain the strengthening cap on the slotted cap after the capping has been effected.

The sleeve 6 may be open at each end extending the whole length of the cap or built only as a ring on the top of the cap where the glass is cemented on the cap, or as shown in Figs. 1, 2, and 6 the sleeve may be closed at its lower end perforations 6a being provided for the passage of the pins 4. Alternatively the sleeve as shown in Fig. 7, may be provided at its lower end with an internal flange 8.

Preferably the pins will be simple rods split or unsplit and the wires are soldered near the bottom of the cap, or alternatively they may be tubes or tubes with longitudinal slots.

Instead of extending to the pins 4 the slots 3 may stop at any point on the surface of the cap, the surface of the cap from this point to the pin being grooved to accommodate the wire. An arrangement where the grooves start at a point short of the pins is illustrated in Fig. 8 of the accompanying drawings, where 10 indicates the grooves for the wires. If desired instead of slotting the body of the cap, grooves may be provided as indicated in Fig. 9 where a groove 11 is formed in the body of the cap from which a second groove 12 extends to the pin 4.

As already stated when applying the cap to the valve, the leading in wires a as they leave the valve are passed through the slots 3 or laid in the grooves 10 or 11 as the case may be, the ends of said wires being either passed through the slots 9 in the pins and soldered to the ends of said pins, or where the pins are not slotted, the ends of the wires may be soldered to the pins at some convenient point.

In the case of valves having the contacts at the side of the cap as shown in Figs. 10 and 11, the contacts indicated by 12 are secured in the known manner to the cap, the leading in wires being passed through slots 3 in the sides of the cap and their ends soldered to the side contacts. It may be advisable to use slotted side contacts having a groove 13, on the bottom in which the end of the wire may be laid and soldered. This has the advantage that all contacts can be soldered to the wires by dipping them in a solder bath in one operation.

Such an arrangement as that just described is shown in Figs. 12 and 13 of the accompanying drawings.

I claim:

1. For an electronic tube having leading in wires, a cap comprising a side wall and a bottom, contacts on said cap adapted to be connected with said leading in wires, and incisions in the side wall and in the bottom of said cap, extending from the open end of the cap longitudinally of said cap to its bottom and across said bottom to one of said contacts.

2. For an electronic tube having leading in wires, a cap comprising a side wall and a bottom, contacts on said cap adapted to be connected with said leading in wires, incisions in the side wall of said cap, said incisions reaching from the outside through at least part of the thickness of said wall and extending each from the open end of the cap longitudinally of said cap and to one of said contacts, a portion of each incision which starts at the open end of said cap being in

the form of a slot and the remaining portion of each incision being in the form of a groove.

3. For an electronic tube having leading in wires, a cap comprising a side wall and a bottom, contacts on said cap adapted to be connected with said leading in wires, slots in the side wall of said cap extending each from the open end of the cap longitudinally of said cap, and a reinforcing sleeve fitting over said cap.

4. For an electronic tube having leading in wires, a cap comprising a side wall and a bottom, contacts on said cap adapted to be connected with said leading in wires, a slot in each contact, incisions in the side wall of said cap, said incisions reaching from the outside of said side wall through at least part of the thickness thereof and extending each from the open end of the cap longitudinally thereof and to the slot.

5. For an electronic tube having leading in wires, a cap comprising a side wall and a bottom, contact pins on the bottom of said cap adapted to be connected with said leading in wires, each of said contact pins having a longitudinal incision, and incisions in the side wall and in the bottom of said cap and extending each from the open end of the cap longitudinally of said cap to its bottom and across said bottom to one of said contact pins.

6. For an electronic tube having leading in wires, a cap comprising a side wall and a bottom, hollow contact pins on the bottom of said cap adapted to be connected with said leading in wires, each of said contact pins having a longitudinal slot, incisions in the side wall and in the bottom of said cap and extending each from the open end of the cap longitudinally of said cap to its bottom and across said bottom to the slot of one of said hollow contact pins.

7. For an electronic tube having leading in wires, a cap comprising a side wall and a bottom, side contacts on said cap adapted to be connected with said leading in wires, each of said side contacts having an incision at least at its bottom, incisions in the side wall of said cap, said latter incisions reaching from the outside through at least part of the thickness of said wall and extending each from the open end of the cap longitudinally of said cap and to the incision in one of said side contacts.

8. For an electronic tube having leading in wires, a cap comprising a side wall and a bottom, contact pins on the bottom of said cap adapted to be connected with said leading in wires, incisions in the side wall of said cap, said incisions reaching from the outside through at least part of the thickness of said wall and extending each from the open end of the cap longitudinally thereof, and a reinforcing sleeve fitting over said cap, said sleeve having a bottom part provided with individual holes for the passage of said contact pins.

9. For an electronic tube having leading in wires, a cap comprising a side wall and a bottom, contact pins on the bottom of said cap adapted to be connected with said leading in wires, incisions in the side wall of said cap, said incisions reaching from the outside of said side wall through at least part of the thickness thereof and extending each from the open end of the cap longitudinally thereof, and a reinforcing sleeve fitting over said cap, said sleeve having a bottom part with a common opening for the passage of all said contact pins.
